UNITED STATES PATENT OFFICE

ERNST OSCAR NEBEL, OF PHILADELPHIA, PENNSYLVANIA

METHOD OF FORMING OPEN-WORK DESIGNS IN STOCKINGS

Application filed June 30, 1928. Serial No. 289,465.

This invention relates to a method for producing open-work designs in knitted fabrics, especially full-fashioned hosiery.

The method forming the subject of my invention comprises the knitting of a fabric in a plurality of different parts or sections, and causing the selvage edges of these different parts to be tied together, or to overlap and to be interknit with each other, at predetermined intervals, whereby the several sections of the fabric are tied together to form the whole of the fabric whereby holes or openings are formed between the sections in a manner to produce artistic designs in the fabric, the said openings having selvage edges throughout.

Referring to the drawings:

Fig. 1 is a side view of a stocking having an open-work design formed therein in accordance with the principles of my invention;

Fig. 2 is a diagrammatic view illustrating the use of a plurality of threads in the formation of a portion of the design shown in Fig. 1;

Fig. 3 is an enlarged diagrammatic view of the stitch formation at one of the openings constituting the design; and

Fig. 4 is a diagrammatic illustration of a machine "set up" capable of producing the design shown in Fig. 1.

This invention is shown in the drawings as being applied to a flat full-fashioned hosiery knitting machine, in which the thread bars are adapted to be longitudinally reciprocated, in the usual manner, by mechanism not shown, the thread bars being provided with the usual thread guides or fingers which are adapted to lay knitting threads between the needles 1 and the forward ends of the sinkers 2.

In order to knit a stocking having an open-work design formed therein, according to the principles of my invention, the thread guide 10, in the present instance, is adapted to deliver a knitting thread to the needles for the knitting of the leg portion A of the stocking, down to the line a, in the usual manner.

To this point in the operation the thread

bar 11, which carries the guide 10, is controlled by the usual screw and nut mechanism (not shown) whereby the selvage edges x, x of the stocking blank are formed.

When the knitting progresses to the course at the line a the screw and nut control for the thread bar 11 is thrown out of action and a controlling mechanism 15, such as that illustrated in my co-pending application, Serial No. 239,554, filed December 12, 1927, is brought into action.

At the same time a similar thread bar controlling mechanism 25 is brought into action for controlling the reciprocation of thread bars 21, 21 on which are mounted thread guides 20, 20, respectively.

The thread guide 10 is thereafter adapted to feed a knitting thread to the needles which knit the center portion B of the stocking; and the thread guides 20, 20 are respectively adapted to feed threads to the needles which knit the portions C, C of the stocking lying between the center portion B and the selvage edges x, x.

The machine is adapted to then knit a number of courses, in the present instance four, which produces a hole D intermediate the portions B and C, having selvage edges, as shown in Fig. 3.

The controlling mechanism 15 is so arranged that during the knitting of the next four courses the thread guide 10 will travel to each side of the portion B overlapping the portions C, C to the extent of two wales or needles, in the present instance.

This running of the thread which forms the center portion B, into the portions C, C at the opposite sides of the portion B ties these portions B and C of the fabric together and completes the hole D.

At this time another thread bar controlling mechanism 35 is brought into action to form a portion E of the fabric which lies between the portions B and C, and is outlined by a series of holes D.

For the purpose of laying threads of certain of the needles to form the portions E of the fabric, the controlling device 35 is operatively associated with thread bars 31, 100

31 on which are respectively mounted thread guides 30, 30.

Each of the thread bar controlling devices 15, 25 and 35 comprises a pair of endless chains or belts 16, 16 on which are secured abutment blocks 17, 17 of various lengths. The chains 16 and the blocks 17 thereon are adapted to be intermittently moved between the reciprocations of the thread bars to present the blocks 17 successively to stop screws or similar elements 18, 18 which are operatively connected to the thread bars 11, 21 and 31 respectively.

The various lengths of the abutment blocks 17 permit the thread bars, which they respectively control, to be moved across different numbers of the needles in order to form the holes or openings D at desired places, and to effect the overlapping of the various portions of the fabric to complete the holes and tie the different parts of the fabric together.

Where a hole is to be formed the thread bar controlling elements so regulate the travel of the different thread bars that the thread guides carried thereby are caused to be stopped between a given pair of adjacently positioned needles at the end of one of their reciprocatory movements, whereby, when the thread bars travel in the opposite direction no thread is laid between the said pair of adjacently positioned needles which consequently produces a hole D in the fabric having a selvage edge. This operation is continued for a given number of courses depending upon the length of the hole to be produced whereupon one or both of the thread bars are adapted to travel across the space between the two said adjacently positioned needles into the adjacent portion of the fabric to tie the adjacently positioned portions of the fabric together, as illustrated at *a* in Fig. 3, to form the whole of the fabric.

For the purpose of illustrating the operations attending the formation of the design illustrated in Fig. 1, when the course illustrated by the line *a* is reached the operation of the thread guide 10 is changed, and the thread guides 20, 20 thrown into action as above noted, whereupon the machine is started.

The machine then knits four courses, the thread guide 10 delivering thread to the needles to produce the central portion B of the stocking blank and the thread guides 20, 20 respectively delivering threads to the needles which produce the side portions C of the fabric.

At the completion of the fourth course the thread guide 10 is caused to travel across the needles, at each side of the portion B, which produce the portions C, C, to the extent of two needles, or two wales of the portions C, C of the fabric, thus the

end of the first hole D is produced and the portions C, B, C of the fabric are tied together.

The overlapping of the different portions of the fabric is diagrammatically illustrated in Fig. 2 and in detail in Fig. 3.

The thread guides 30 are then thrown into action to produce the portions E, E of the fabric. The machine is adapted to then knit four courses, with the guide 10 overlapping the portions C, C of the fabric as noted during the knitting of these four courses. During the knitting of these four courses the thread of which the portion E is composed is being interknit with these overlapping portions of the fabric to anchor the said thread end in the fabric.

During the knitting of the next four courses the thread guides 10, 20 and 30 are controlled in the manner above noted to produce the portions B, C, C and E, E, these portions of the fabric being separated by the holes D¹, D¹.

During the knitting of the next four courses, the thread guide 10 overlaps the portion E to tie the parts B and E, E together as above noted, and the thread guides 20, 20 are caused to overlap the opposite sides of the portions E, E to tie the parts C, C and E, E together.

These actions of the respective thread guides are controlled by the different length abutment blocks 17 being moved into alignment with the stops 18, respectively connected to the different thread bars on which the thread guides 10, 20 and 30 are carried.

The knitting of the fabric in the above manner continues, alternating every four courses to form holes and to tie the fabric together between the holes, until the line *b* is reached, whereupon the thread guides 30 are thrown out of action and the thread guides 10 and 20 proceed to form the portions B¹ and C¹ of the fabric, in the manner noted, until the line *c* is reached.

When the line *c* is reached the thread guides 30 are again thrown into action to produce the portion E¹ of the fabric and the thread guides 10 and 20 controlled to form the fabric portions B² and C² respectively.

The knitting progresses in this manner until the line *d* is reached, whereupon the guides 30 are again thrown out of action and the guides 10 and 20 again co-operate to form the portions B³ and C³ of the fabric.

When the line *e* is reached the thread guides 30 are again thrown into action to produce the portion E² in the manner above noted, the thread guides 10 and 20 producing the portions B⁴ and C⁴ respectively, and when the line *f* is reached the thread guides 20 and 30 are thrown out of action and the thread guide 10 is employed to feed yarn to all the needles between the selvage edges *w*, *x* of the fabric to form the portion A¹ there-

of, after which the knitting of the remainder of the stocking is effected in the usual manner, the controlling mechanism 15 for the guide 10 being replaced again by the common screw and nut controlling mechanism of the machine.

While I have described the operations attending the formation of the design shown in Fig. 1, obviously any desired form of design may be produced in a like manner, by changing the arrangement and lengths of the abutment blocks 17, and while I have described the operation as alternating at every fourth course to produce either a hole or an overlapping tie portion of the fabric, this relation may also be changed in accordance with the length of the hole desired and the length of the overlapping portions desired to obtain between the holes.

From the above it will be seen that I am able to produce open-work designs of designs of desired configurations by producing a fabric consisting of a plurality of different portions tied together at desired points to complete the fabric and to form the open-work at desired points between the different portions of the fabric.

I claim:

1. A method of producing open-work designs in knitted fabric, comprising the knitting of a fabric in a plurality of separate independent sections each section having selvage edges, and interknitting the selvage edges of adjacent sections at predetermined intervals.

2. A method of producing open-work designs in knitted fabric, comprising the knitting of a fabric in a plurality of separate independent sections simultaneously, each section having selvage edges extending wale-wise of the fabric, and overlapping and interknitting the selvage edges of adjacent sections at predetermined intervals wale-wise of the fabric.

3. A method of producing open-work designs in knitted fabric, comprising the knitting of a fabric in a plurality of separate independent sections simultaneously, each section having selvage edges extending wale-wise of the fabric, producing course-wise extensions at predetermined wale-wise intervals on at least one of said sections adapted to overlap an adjacent section, and interknitting the said extensions with the fabric of the adjacent section which they overlap, to tie the sections together at predetermined intervals to form selvage edged openings in the fabric.

4. A method of producing open-work designs in knitted fabric, comprising the knitting of a fabric in a plurality of separate independent sections simultaneously, each section being formed of an independent thread, carrying the thread of at least one of said sections across at least one of the

wales of an adjacent section at predetermined intervals throughout the knitting operation, and interknitting the said overlapping thread with the thread of the overlapped section to tie the sections together at predetermined intervals wale-wise of the fabric to form openings in the fabric.

5. A method of producing open-work designs in stockings, comprising the knitting of one portion of a stocking of a single thread, and knitting another portion of the stocking in a plurality of separate independent sections integrally connected to the first said portion of the stocking, all the courses of each separate independent section being formed of a separate thread, carrying the thread of one section across at least one wale of an adjacent section at predetermined intervals throughout the knitting operation and interknitting the overlapping thread of the one section with the thread of the overlapped section to tie the sections together at predetermined intervals wale-wise of the stocking to form open-work designs in the stocking.

6. A method of producing open-work designs in stockings, comprising the knitting of one portion of a stocking of a single thread, and knitting another portion of the stocking in a plurality of separate independent sections integrally connected to the first said portion of the stocking, all the courses of each separate independent section being formed of a separate thread, carrying the thread of one section across at least one wale of an adjacent section at predetermined intervals throughout the knitting operation and interknitting the overlapping thread of the one section with the thread of the overlapped section to tie the sections together at predetermined intervals wale-wise of the stocking to form open-work designs in the stocking, employing the thread of which the first said portion of the stocking is composed to form one of the separate independent sections of the second said portion of the stocking.

7. A method of producing open-work designs in stockings, comprising the knitting of one portion of a stocking of a single thread, and knitting another portion of the stocking in a plurality of separate independent sections integrally connected to the first said portion of the stocking, all the courses of each separate independent section being formed of a separate thread, carrying the thread of one section across at least one wale of an adjacent section at predetermined intervals throughout the knitting operation and interknitting the overlapping thread of the one section with the thread of the overlapped section to tie the sections together at predetermined intervals wale-wise of the stocking to form open-work designs in the stocking, employing the

thread of which the first said portion of the stocking is composed to form one of the separate independent sections of the second said portion of the stocking, and employing the same thread to produce a third portion of the stocking extending entirely across the stocking and integrally connecting the said independent sections of the second part to the said third part of the stocking by interknitting the threads of which the independent sections are composed with thread of which the third portion of the stocking is composed.
